INTERMITTENT CERVICAL TRACTION
APPARATUS

Louis Yellin, Philadelphia, Pa.

Application November 15, 1950, Serial No. 195,766

2 Claims. (Cl. 128—75)

1

My invention relates to a traction apparatus used to relieve pain and suffering of a patient, and relates particularly to an apparatus which applies an intermittent traction to the vertebrae of the neck for treating persons afflicted with a ruptured or herniated cervical disc.

Heretofore, apparatus for applying a constant traction to the neck of a patient was used and was a valuable procedure for a ruptured or herniated cervical disc. The herniation causes pressure against the ligaments and nerve roots causing intense pain to radiate through the neck, shoulder girdle, chest, and upper limb extremities. This pain is often associated with narrowing of the intervertebral interspaces which are readily discernible by the use of X-rays. The application of a constant traction to the neck increased the width of the intervertebral interspaces and removed the pressure from the nerve roots and ligaments, and allowed the herniated disc to recede back into the interspace to assume its normal position. The prior methods were efficacious, but they caused great discomfort to the patient as the straps of the head halter usually placed pressure on the jaw and face until they ached, as well as compressing the jugular vein and causing the patient to have headaches. Therefore, many patients were unable to bear the constant pressure of the constant traction method and the apparatus had to be removed from time to time which retarded the healing of the ruptured cervical disc because as soon as the head halter or straps were removed, the cervical disc was again subjected to compression and protrusion from between the vertebrae.

It, therefore, is an object of my invention to provide a traction apparatus for treating persons afflicted with a ruptured or herniated cervical disc which applies an intermittent traction to the neck of the patient.

Another object of my invention is to provide a traction apparatus for treating persons afflicted with a ruptured cervical disc which can apply intermittent traction loads for long periods of time to the neck of the patient, without discomfort to the patient.

Another object of my invention is to provide a traction apparatus for treating persons afflicted with a ruptured cervical disc which can apply remittent traction loads continuously to the neck of a patient while the patient is confined to a hospital.

Other objects of my invention are to provide a traction apparatus for treating persons afflicted with a ruptured cervical disc which is easily and economically produced, which is sturdy in construction, and which is highly effective in use.

With the above and related objects in view

2

my invention consists in the details of construction and combination of parts as will be more fully understood from the following description when read in conjunction with the accompanying drawing, in which:

Fig. 1 is a perspective view of a traction apparatus embodying my invention.

Fig. 2 is a rear view of the patient support of Fig. 1.

Fig. 3 is a side view of the patient support of Fig. 1.

Referring now in greater detail to the drawing wherein similar parts are designated by similar reference characters, I show a patient support, generally designated as A, which is illustrated as a chair in Figs. 1, 2 and 3, but which may be a bed or other structure, having traction apparatus, generally indicated as B, mounted on said patient support A, a suitable electric motor, generally designated as C, to actuate the traction apparatus B, and a traction load indicating member, generally designated as D, as well as a patient, generally designated as E, whose head and neck are enclosed by a head halter, generally designated as F, which is attached to the traction apparatus B.

The patient support A may be of any design or construction such as a chair, as illustrated, a bed, or a table, so long as it supports the patient comfortably. The patient support A has attached to the back of it by any suitable means and substantially in line with the neck of the patient E, the traction apparatus B.

The traction apparatus B comprises a pair of telescoping interfitting pipes 10 and 12, respectively, which may be longitudinally adjusted by means of a thumb or set screw 14. The pipes are loosely fitted to permit one pipe 12 to slide into the pipe 10 to shorten the overall length, or vice versa. The thumb screw 14 when tightened locks the pipes 10 and 12 together.

One end 16 of the pipe 10 is attached to the patient support A by any suitable means, so that the pipe 10 lies in substantially the same plane as the neck of the patient E. The end 18 of the pipe 10 has a screw 14 passing through the wall of the pipe 10 so that the end of the screw 14 engages the pipe 12 to secure the pipes 10 and 12 together. The free end 20 of the pipe 12 (the end protruding from the pipe 10) has a pulley mounted upon it. The pulley 22 may be mounted by means of a bracket attached to the free end 20 of the pipe 12, in any manner well known to the art, as the manner of fastening or mounting this pulley forms no part of the invention and any manner of attaching the pulley 22 may be utilized. An arm 24 extending perpendicular to the pipe 12 is securely attached

to the free end 30 of the pipe 12 in such a manner that it will not interfere with the operation of the pulley 22. The arm 24 has mounted on its free end a pulley 26. In the illustration of Fig. 1, I show the pulleys 22 and 26 mounted on the arm 24.

A rope, cord, or cable 30 is passed through the pipes 10 and 12 and over the pulleys 22 and 26. One end of the rope 30 is attached to an eccentric shaft 32 mounted on a disc 34 which is driven by a speed reduction unit 36 which is attached to the motor C. The end 30A of the rope 30 is attached to the eccentric shaft 32 in any suitable manner.

The motor C coupled to the speed reduction unit 36 and the disc 34 and its eccentric 32 apply intermittent or remittent traction force to the rope 30. This pulling traction unit is mounted on, or near, the patient support A in any suitable manner. The manner of mounting the motor or place of mounting the motor forms no part of this invention and will not be discussed in great detail here, as any method of mounting, or place of mounting may be selected so long as a pulling force is exerted on the rope 30. The motor C may be of any type such as an electric motor, or it may be replaced with a mechanical or hydraulic unit. It should be apparent that any type of force which can impart an up and down motion or traction to the rope may be employed. The motor C illustrated is an electric motor which drives a speed reduction unit 36 attached thereto, which in turn drives the disc 34 imparting an up and down motion to the eccentric shaft 32 mounted on the disc 34 whereby each cycle of the eccentric applies a pull, then a recession on the rope 30.

The other end 30B of the rope 30 is attached to one end of a spring tension indicator D which is provided with a hook 31A to which the end 30B is attached in any suitable manner. The spring tension indicator D is constructed on the principle of the spring scale, but the indicator D is provided with a spring of sufficient strength so that all desirable traction loads are covered. The spring (not shown) in the scale provides for the traction force being resiliently applied to the harness F. The tension in the pounds applied to the patient can be read directly upon the tension indicator D, thus, making it possible to ascertain the traction load at a glance. It should be kept in mind that the indicator D may be placed anywhere along the rope 30, although it is illustrated at the end 30B of the rope 30.

The other end of the tension indicator D has secured to it by means of the eye 31B and hook 33, a yoke 28 to which a head halter F is attached. The yoke 28 is provided with a series of teeth 29 at each end so that the head halter straps may be secured to the yoke 28.

The head halter F is of conventional design and passes around and under the chin and jaw, as well as around the neck of the patient E.

The operation of my invention is as follows:

A patient E is seated or lies on the patient support A, and the head halter F is placed around the head and neck of the patient E in the manner well known to the art. The head halter F is then fastened to the yoke 28. The proper traction load is then applied to the patient's neck by moving the eccentric shaft 32 on the disc 34 to its lowermost position, i. e., away from the pipe 10, and adjusting the length of the pipes 10 and 12 longitudinally so that the tension indicator D shows the pounds tension required or desired. The pipes 10 and 12

are then locked together by means of the screw 14 and the motor C is started whereby the speed reduction unit is actuated and moves the disc 34 slowly. The rope 30 attached to the eccentric shaft 32 has thus applied to it a maximum traction load at one part of the cycle of the disc 34 and a minimum traction load at another part of the cycle of the disc 34. However, it is pointed out that this change from maximum to minimum traction load is gradual due to the action of the eccentric shaft 32 and the resiliency of the spring indicator D.

It is further pointed out that the maximum traction load and minimum traction load are such that the vertebrate interspaces are continually kept at their greatest width to inculcate healing of the ruptured cervical disc, but not so great that the minimum traction load does not afford relief from pressure of the straps of the head halter. In other words, the minimum traction load is such that it affords relief from pressure of the straps while still maintaining the interspace a sufficient width to promote healing of a ruptured or herniated cervical disc. Thus, the apparatus of my invention may be used for long periods of time without discomfort to the patient.

When the pipes 10 and 12 are extended then greater traction force is applied—likewise, shortening the pipes 1 and 2 causes the traction force to be reduced.

As a modification of my invention the pipes 10 and 12 may be telescopic pipes in a hydraulic system so that pressure in pipe 12 hydraulically may cause the pipe 12 to move thereby moving the rope 30. The motor under such conditions would be eliminated.

Although my invention has been described in considerable detail such description is intended as merely illustrative rather than limiting, as my invention may be variously embodied, and the scope of the invention is to be determined as claimed.

I claim as my invention:

1. In a machine for relieving a person afflicted with a ruptured herniated cervical disc comprising a harness adapted to embrace the chin and neck of said person whereby the neck may be pulled with respect to the person's body, a horizontally located member for seating a person, a post extending vertically of said member, a lateral extension connected to the upper end of said post, a motor beneath said horizontally located member, an eccentric connected to and driven by said motor, a plurality of rollers attached to said post and said extension, and a flexible means connecting said harness to said eccentric and guided by said rollers whereby said motor when rotating imposes a recurrent tension on said harness.

2. The invention of claim 1 wherein said flexible means include a torsion spring.
